L. B. FULTON.
GAS RELIEF VALVE.
APPLICATION FILED JUNE 23, 1913.

1,110,320.

Patented Sept. 15, 1914.

UNITED STATES PATENT OFFICE.

LOUIS B. FULTON, OF PITTSBURGH, PENNSYLVANIA, ASSIGNOR TO THE CHAPLIN-FULTON MANUFACTURING COMPANY, OF PITTSBURGH, PENNSYLVANIA, A CORPORATION OF PENNSYLVANIA.

GAS RELIEF-VALVE.

1,110,320.

Specification of Letters Patent. Patented Sept. 15, 1914.

Application filed June 23, 1913. Serial No. 775,351.

To all whom it may concern:

Be it known that I, LOUIS B. FULTON, of Pittsburgh, in the county of Allegheny and State of Pennsylvania, have invented certain new and useful Improvements in Gas Relief-Valves; and I do hereby declare the following to be a full, clear, and exact description of the invention, such as will enable others skilled in the art to which it appertains to make and use the same.

In the manufacture of gasoline from natural gas it is necessary, after precipitation or liquification, to periodically reduce the pressure of the gas as much as from ten to twenty pounds and for economic reasons care has to be exercised not to allow too great a reduction, since such reductions have involved a waste of gas.

The primary object of my invention is to provide a relief valve which will effect the automatic discharge of the gas, heretofore wasted, into an outlet main from which it may be drawn for any desired purpose.

A further object is to provide a relief valve for the purpose stated which will be wholly automatic in operation, being opened to discharge when the maximum pressure has been attained in the compressor and closed when the necessary reduction has been effected. And a further object is to render the valve adjustable so that the periods of reduction may be shortened or lengthened.

In the accompanying drawing, the figure 35 is a vertical longitudinal sectional view of my improved valve.

Referring to the drawings, 1 designates the casing; 2 the inlet or high-pressure main which leads from a compressor (not shown); 3 the outlet or low-pressure main which may connect with a city or other supply; and 4 the main valve which is normally held to its seat by the pressure at the inlet plus the action of a spring 5.

45 Superposed on the valve-casing is a chamber 6 wherein is a diaphragm 7 which is designed to effect the downward movement of a slideable member 8 and through the latter the tilting of a lever 9 which has an adjustably positioned weight 10 at one end. Into chamber 6 opens one end of a pipe 12 which leads from main 2, and this pipe is also connected to a second diaphragm chamber 13 which is shown as

located between the valve casing and diaphragm chamber 6. The diaphragm 14 in chamber 13 is designed to act downwardly on a vertically slideable member 15 by which the main valve is forced from its seat. The upper end of the member 15 is of greater cross-sectional area than the underside of the main valve.

In the connection between pipe 12 and diaphragm chamber 13 is a high-pressure valve 16 which normally closes communication to said chamber, being held to its seat by a spring. This diaphragm chamber 13 is also connected with the outlet main 3, and in such connection has a low-pressure valve 17 which, in practice, is normally held from its seat by lever 9, but when the unseating means is removed such valve is automatically seated by its spring. The stems of both of these valves, 16 and 17, project beyond the upper ends of their casings, and are shown as being in the same vertical plane so that they may be alternately unseated by lever 9. The latter is shown as having two tappets 18, each of which is adjustable to time the opening and closing of the valves, said tappets being designed to engage the valve stems. The time of engagement may be changed by adjusting the tappets which latter are shown in the form of nutted bolts carried by the lever.

Normally the main inlet valve is held to its seat, as is also the high-pressure valve 16, but the low-pressure valve 17 is normally held unseated by the lever under the action of its weights. Let it be assumed that in the main 2 leading from the condenser there is a maximum pressure of 200 pounds although in actual practice this pressure may be anywhere from 200 to 300 pounds, more or less. When the maximum pressure is attained and it is desired to blow down and thereby decrease the pressure as much as from 10 to 20 pounds, the weight on the lever being properly adjusted, and the proper tension placed on the main valve spring, the apparatus is ready for action. The pressure at the inlet, coupled with the lifting action of the spring, will hold the main valve to its seat. As the maximum pressure is attained it will act downwardly on diaphragm 6, and through the sliding member 7 the weighted lever will be rocked on its fulcrum, thereby unseating the high-

pressure valve 16, and allowing the low-pressure valve 17 to seat. When valve 16 is unseated the pressure in the inlet main will act downwardly on diaphragm 14 and thereby unseat the main valve, allowing the pressure from the inlet side of the main valve to pass into the outlet main wherein the pressure may range from zero to 50 pounds, more or less, and from this main 5 10 15 20 25 30 35 40 45 50 55 60 65 70 75 80 85 90 95 100 105 110 115 120 125 130 pounds, more or less, and from this main the gas may be used for whatever purpose desired. As soon as the necessary reduction of pressure in the inlet main has been attained, the weighted end of the lever will overcome the pressure in diaphragm chamber 6, and upon rocking on its fulcrum the lever will allow the high-pressure valve 16 to be seated and at the same time will unseat the low-pressure valve 17, thereby relieving the pressure in diaphragm chamber 18, and allowing the entrapped gas to pass from such chamber to the outlet main. As soon as this occurs the main valve will immediately be forced to its seat by the out-flowing gas and the uplifting action of its spring.

The advantages of my invention will be readily appreciated by those skilled in the art. All of the parts are quick and positive in operation. This is absolutely essential in a device of this character. The diaphragm 7 which is always subjected to the high-pressure has only a very slight movement, and this movement multiplied by the distance from the center of the diaphragm 30 to the stem of the inlet valve 16 insures the instant opening of the latter. This is also true in respect to the opening of the exhaust valve 17, the quick unseating of which insures the instant closing of the main valve. 35 40 45 50 55 60 65 70 75 80 85 90 95 100 105 110 115 120 125 130

The necessary periodic reductions are insured by automatically-actuating means without any loss of gas whatsoever.

I claim as my invention:

1. A gas relief valve comprising, in combination, a main valve normally held to its seat by pressure at the inlet side thereof, a gas-chamber having movable means for effecting the unseating of said main valve, an inlet valve for said chamber controlling communication between the latter and the inlet side of the main valve, an outlet valve for said chamber controlling communication between the latter and the outlet side of the main valve, and actuating means for alternately acting upon said inlet and outlet valves and arranged to open the inlet valve and close the outlet valve under a predetermined pressure at the inlet side of the main valve and to open the outlet valve and close the inlet valve when the desired reduction in pressure on the inlet side of the main valve has been obtained.

2. A gas relief valve comprising, in combination, a main valve normally held to its seat by pressure at the inlet side thereof,

gas-chamber having movable means for effecting the unseating of said main valve, an inlet valve for said chamber, an outlet valve therefor controlling a connection between said gas-chamber and the outlet side of said main valve, actuating means for said inlet and outlet valves arranged to open the inlet-valve and close the outlet-valve under a predetermined pressure at the inlet side of the main valve and to open the outlet valve and close the inlet valve when the desired reduction in pressure on the inlet side of the main valve has been obtained, and adjustable means for timing the opening and closing of said valves.

3. A gas relief valve comprising, in combination, a main valve normally held to its seat by pressure at the inlet side thereof, a gas-chamber having movable means for effecting the unseating of said main valve, an inlet valve for said chamber, an outlet valve therefor, a connection between said gas-chamber and the outlet side of said main valve, said outlet-valve being located in said connection, a lever for alternately unseating said inlet and outlet valves, said inlet-valve being normally seated, a connection between said gas-chamber and the inlet side of said main-valve in which said inlet-valve is located, and actuating means for said lever constructed and arranged to be operated by pressure from the inlet side of said main-valve.

4. A gas relief valve comprising, in combination, a main valve normally held to its seat by pressure at the inlet side thereof, a gas-chamber having movable means for effecting the unseating of said main valve, an inlet valve for said chamber, an outlet-valve therefor, a lever for alternately unseating said valves, a second gas-chamber having movable means for actuating said lever to unseat said inlet-valve and seat said outlet-valve, and a pipe connecting said second gas-chamber with the inlet side of the main-valve to allow the pressure on said inlet side to enter said gas chamber.

5. A gas relief valve comprising, in combination, a main valve normally held to its seat by pressure at the inlet side thereof, a gas-chamber having movable means for effecting the unseating of said main-valve, an inlet valve for said chamber, an outlet-valve therefor controlling a connection between said gas-chamber and the outlet side of said main valve, a lever for alternately unseating and seating said valves, a second gas-chamber having movable means for actuating said lever to unseat said inlet-valve and seat said outlet-valve, and a pipe connecting said second gas-chamber with the inlet side of the main-valve to allow the pressure on said inlet side to enter said gas chamber.

6. A gas-relief valve comprising, in com-

bination, a main valve normally held to its seat by pressure at the inlet side thereof, said inlet side being designed to be connected to a gas compressor, a gas-chamber having a movable diaphragm, a sliding member designed to be actuated by said diaphragm to unseat said main valve, a gas inlet-valve and a gas outlet-valve for said gas-chamber, a connection between the latter and the outlet side of the main valve, said outlet-valve being located in said connection, a lever for alternately unseating said inlet and outlet valves, a second gas-chamber having a movable diaphragm, a sliding member actuated thereby for shifting said lever, a pipe connecting said second gas-chamber with the inlet side of said main-valve, and a connection between said pipe and the first mentioned gas-chamber wherein said inlet-valve is located.

7. In a gas relief-valve, a main-valve, a gas-chamber having movable means for un-

seating said main-valve against the inlet pressure, a connection between said gas-chamber and the inlet side of said main valve, an inlet-valve in said connection, a connection between said gas-chamber and the outlet side of the main valve, an outlet-valve in said latter connection, said inlet and outlet valves having projecting stems, a lever having adjustable tappets for engaging said stems, and actuating means for said lever constructed and arranged to cause the latter to open the inlet-valve and close the outlet-valve under a predetermined pressure at the inlet side of the main valve.

In testimony whereof, I have signed this specification in the presence of two subscribing witnesses.

LOUIS B. FULTON.
